UNITED STATES PATENT OFFICE.

HARRY H. CAMPBELL, OF WASHINGTON, DISTRICT OF COLUMBIA, AND WALTER C. FELLOWS, OF PHILADELPHIA, PENNSYLVANIA, ASSIGNEES TO THE COIN DEVICES COMPANY, OF WASHINGTON COURT HOUSE, OHIO, A CORPORATION OF OHIO.

COIN-SEPARATOR.

1,066,076.

Specification of Letters Patent.

Patented July 1, 1913.

Application filed September 29, 1911. Serial No. 652,013.

To all whom it may concern:

Be it known that we, HARRY H. CAMPBELL, a citizen of the United States, residing at Washington, in the District of Columbia; post-office address No. 3304 Sixteenth street northwest, and WALTER C. FELLOWS, a citizen of the United States, residing at Philadelphia; in the State of Pennsylvania, post-office address 3822 Gratz street, have invented certain new and useful Improvements in Coin-Separators, of which the following is a specification.

The present invention relates to improvements in apparatus for separating coins of different sizes and the object is to first separate the largest coins from the rest, then the next largest in order to prevent any piling up of the coins on top of each other.

One embodiment of this invention is illustrated in the drawing, where—

Figure 1 is a top plan view with a part cut away, Fig. 2, a side elevation with the side of the casing removed, Fig. 3, a vertical section at 3—3 of Fig. 1, Fig. 4, a section in larger scale at 4—4 of Fig. 1, Fig. 5, a longitudinal section at 5—5 of Fig. 1 also in larger scale and Fig. 6, a section in larger scale, of the trough along line 6—6 of Fig. 1. Fig. 7, a top plan view in larger scale of a detail of the apparatus; Fig. 8, an elevation, partly in section of Fig. 7; Fig. 9, a cross section at IX—IX of Fig. 7, looking in the direction against arrow 33; Fig. 10, a similar section at X—X and Fig. 11, another similar section at XI—XI.

The apparatus is inclosed in an outer casing 7 provided with a slidable top or tray 8 running in guides of the casing 7. On this tray the coins to be sorted are dumped down. As shown in Figs. 1 and 2 the tray is drawn out, the stop 32 limiting its outward movement and the apparatus ready for use. When not in use, the tray is pushed in, forming the top of the housing and making the apparatus dust proof. The tray has, on three sides low, upright walls 9, terminating on one side with a diagonal partition 10 leaving an entrance opening at 11 through which the coins are fed by hand to the inclined, flat-bottomed trough 12. This trough is joined to the upper end of the chute proper 13 and has an opening 14 in the inner wall 15 see Fig. 6. The height of

the opening has to be a little more than the thickness of the largest coin to be separated and the width of the opening is equal to the width of the chute 13, that is, somewhat wider than the diameter of the largest coin. The object of this is to provide a scraper, that will prevent two coins, one on top of the other to enter the chute proper. Along its whole course the bottom of the chute is inclined crosswise, see Fig. 4, with the lower edge outward and also lengthwise as shown. From the junction between the chute 13 and the trough 12, the bottom of the latter runs upward smoothly in continuation of the chute bottom.

A switch plate 16, touches the bottom of the chute at 17, and has an approximately horizontal bottom see particularly Figs. 7 to 11. The distance from the outer wall of the chute 13 to the flange 18 of the switch plate has to be slightly more than the diameter of the largest coin to be taken out. As a consequence, when the coins travel along the bottom of the chute, those of the largest diameter will slide up on the plate 16 but the next largest ones and all the smaller coins will pass under this switch plate, see Fig. 4. An opening 19 through the side with an extension slit 19^a at the upper end and at an inclination thereof connects the switch with the guide 20, which leads down to a receptacle 21. Guided by the flange 18, the coins that have entered on the switch plate 16 will then pass through the opening 19, and by way of the guide 20 into the receptacle 21. A coin not having speed enough to entirely mount the switch plate 16, will fall out through the slit 19^a. The coins of the next largest diameter will similarly be switched off the chute proper by the plate 22 and carried by the guide 23 into the receptacle 24.

In the bottom of the chute proper are a number of slits or long openings suited to the size of the coin for which they are intended, so that opening 25 would have a width that is suited to the diameter of the smallest coin, and opening 28 suited to the next largest coin. Guides 26, 29 and receptacles 27, 30 respectively are furnished for these coins similarly to what has been described above. The order of separation will, as a consequence, be as follows: The largest

coins are first taken off, second the smallest; third the next largest, fourth the next smallest, etc. The coins left to the last will drop down into receptacle 31.

5. We claim:

1. In a coin sorting apparatus, the combination with an inclined coin chute of a slideable coin receiving tray, a railing around said tray, a gate in the railing, said tray adapted to have two extreme positions, one closing the apparatus and the other the operating position with the gate of the tray registering with the entrance to the chute.

2. In a coin sorting apparatus, the combination with an inclined coin chute for sorting the coins, of a coin tray on which the coins to be sorted are deposited by hand, said tray being slideable in a straight line and adapted to discharge the coins at one end and to have two extreme positions, one for closing the apparatus and the other for operating it, said tray, in the operating position, having its discharge end in delivering relation to the entrance of the chute.

3. In a coin sorting apparatus, the combination with an inclined coin chute constructed to sort the coins, of a slideable coin tray whereon the coins to be sorted are deposited by hand, said tray being slideable in a straight line and adapted to discharge the coins at one end and to have two extreme positions, one for closing the apparatus and the other for operating it; said tray in the operating position having its discharge end in delivering relation to the entrance of the chute; and said tray having a stop adapted to arrest the tray when the discharge end of the tray stands in delivering relation to the entrance of the chute.

4. In a coin sorting apparatus, a plurality of coin directing tracks for coins of different diameters adapted to receive and support the coins by their flat faces; said tracks being located in consecutive order one after the other in the path of the advancing coins and constructed with their supporting faces digressing vertically; with the track for the greater coin above that for the less, and with an opening in the bottom of the greater coin track at the place of digression to permit the lesser coins to follow the lower track.

5. In a coin sorting apparatus, a continuous main coin chute, and a plurality of coin directing tracks within the main chute for coins of different diameters and adapted to receive and support the coins by their flat faces; said tracks being constructed with their supporting faces digressing vertically from said main chute; with the track for the greater coin preceding that for the less, and with an opening in the bottom of the greater coin track at the place of digression to permit the lesser coins to follow the main chute.

6. In a coin sorting apparatus, the combination with a contiguous main coin chute, the bottom of said chute being suitably inclined in its longitudinal direction and adapted to convey the coins in a flat position, a coin switch located within said main chute in the path of the advancing coins; said switch being constructed to receive coins of larger diameter, and support them by their flat faces, and direct them from the chute.

7. In a coin sorting apparatus, the combination with a continuous main coin chute, having its bottom suitably inclined in its longitudinal direction, and constructed of a width sufficient to accommodate a coin of any size sliding flat thereon; of a plurality of coin switches located in consecutive order one after the other in the path of the advancing coins within said main chute, and adapted, respectively, to deflect coins from the chute in the order of their diametric measurement; said switches being each constructed to support the coins deflected thereby, and to permit all smaller coins to continue to slide down the chute.

8. In a coin sorting apparatus, the combination with a continuous main coin chute, having its bottom suitably inclined in its longitudinal direction, and constructed of a width sufficient to accommodate a coin of any size sliding flat thereon; of a plurality of coin switches located in consecutive order, one after the other in the path of the advancing coins within said main chute, and adapted, respectively, to deflect coins from the chute in the order of their diametric measurement; said switches being each constructed to support the coins deflected thereby, and each having beneath it a passageway for coins of less diameter, whereby it permits the latter to continue down the chute.

9. In a coin sorting apparatus, the combination with a coin chute having its bottom constructed to support coins lying down on their flat faces, and suitably inclined in its longitudinal direction, of a straight sided entrance trough set at an angle of approximately 90° horizontally to the direction of the chute so as to abruptly change the direction of the advancing coins, the bottom of said trough forming an unbroken continuation of the upper end of the bottom of said chute, and the straight continuation of one side of said trough forming a barrier located in the length direction of said trough and above the chute a distance to admit the coins edgewise beneath it.

10. In a coin sorting apparatus, the combination with a coin chute having its bottom constructed to support coins by their flat faces, and suitably inclined in its longitudinal direction, of an entrance trough set at an angle horizontally to the direction

of the chute, the bottom of said trough forming an unbroken continuation of the upper end of the bottom of said chute, and a barrier located above the chute a distance to admit the coins edgewise beneath it; said barrier being formed by a continuation of a side wall of the entrance trough.

11. In a coin sorting apparatus, the combination with a coin chute, the bottom of said chute being inclined in its longitudinal direction and adapted to convey the coins slidingly on their flat faces, a plurality of coin switches located in the path of the advancing coins, said switches adapted to lead the coins of the largest diameter sliding on their flat faces out from the chute and to permit all smaller coins to pass under the switch and to continue to slide down the chute, a straight entrance trough set at an angle of approximately 90° to the horizontal direction of the chute, the bottom of said trough forming an unbroken continuation of the upper end of the bottom of said chute, and a scraper across the chute formed by the continuation of one side wall of said trough.

12. In a coin sorting apparatus, the combination with a coin chute, the bottom of said chute being inclined longitudinally and adapted to convey the coins slidingly upon their faces, of an outwardly turned coin switch located in the path of the advancing coins, and adapted to raise the flat lying coins of the largest diameter from the chute and deflect said coins outwardly; there being a side wall extending upwardly to confine the raised coins upon the switch and said side wall having an opening opposite the out-turned portion of the switch.

13. In a coin sorting apparatus, the combination with a coin chute, the bottom of said chute being inclined longitudinally and adapted to convey the coins slidingly upon their faces, of an outwardly turned coin switch located in the path of the advancing coins, and adapted to raise the flat lying coins of the largest diameter from the chute and deflect said coins outwardly; there being a side wall extending upwardly to confine the raised coins upon the switch and said side wall having an opening opposite the out-turned portion of the switch; said opening being at its upper end extended below the coin supporting surface of the switch.

14. A coin separator comprising a main chute, in position to afford vertical support to one of the flat faces of the coin, and a plurality of diverting chutes, each constructed to receive and afford vertical support to the flat faces of a particular size of coin, arranged in series in the order of the sizes of the coin received, each with its supporting surface at the receiving end merged with the supporting surface of the main chute,

and diverted gradually upward therefrom to lift and remove its appropriate coin from the main chute.

15. A separator for coins or other tokens comprising a main chute in position to afford a vertical support to the flat side of the coin, and a diverting chute constructed to receive and afford vertical support to the flat side of the coin having its supporting surface at its receiving end merged with the surface of the main chute, and gradually diverted upwardly therefrom, whereby it gradually lifts and removes the particular coin from said main chute.

16. A separator for coins or other tokens comprising a main chute, in position to afford a vertical support to the flat side of the coin, and a diverting chute constructed to receive and afford vertical support to the flat side of the coin having its supporting surface at its receiving end merged with the surface of the main chute, and gradually diverted upwardly therefrom, whereby it gradually lifts and removes the particular coin from said main chute, said diverting chute having its receiving end restricted transversely at the point of merging with the main chute to raise the coin to be deflected at the point farthest from the outside wall of the main chute, and to permit all but said particular coin to continue their progress in the main chute.

17. A separator for coins or other tokens comprising a main chute in position to afford a vertical support to the flat side of the coin, and a diverting chute constructed to receive and afford vertical support to the flat side of the coin having its supporting surface at its receiving end merged with the surface of the main chute, and gradually diverted upwardly therefrom, whereby it gradually lifts and removes the particular coin from said main chute, said diverting chute being transversely deflected as regards the main chute to effect lateral removal of the coins.

18. A separator for coins or other tokens comprising a main chute in position to afford a vertical support to the flat side of the coin, and a diverting chute constructed to receive and afford vertical support to the flat side of the coin having its supporting surface at its receiving end merged with the surface of the main chute, and gradually diverted upwardly therefrom, whereby it gradually lifts and removes the particular coin from said main chute, said main chute being curved transversely and said diverting chute being directed toward the outer curve limit of the main chute.

19. A separator for coins or other tokens comprising a main chute, in position to afford a vertical support to the flat side of the coin, and a diverting chute constructed to receive and afford vertical support to the flat side of the coin having its supporting surface at its receiving end merged with the surface of the main chute,

surface at its receiving end merged with the surface of the main chute, and gradually diverted upwardly therefrom, whereby it gradually lifts and removes the particular 5 coin from said main chute, said diverting chute having its receiving end restricted transversely at the point of merging with the main chute to raise one end of the deflected coin first, and to permit the passage 10 of coins that are to remain in the main chute, said main chute being curved transversely, and said diverting chute being directed toward the outer curve limit of the main chute, whereby the not yet deflected 15 coins are kept by centrifugal force away from the lifting surface at the point of merging.

20. A separator for coins or other tokens comprising a main chute in position to afford a vertical support to the flat side of the coin, and a diverting chute constructed

to receive and afford vertical support to the flat side of the coin having its supporting surface at its receiving end merged with the surface of the main chute, and gradually 25 diverted upwardly therefrom, whereby it gradually lifts and removes the particular coin from said main chute, said diverting chute having a laterally deflecting wall in position to engage the edge of the separated 30 coin and guide it laterally.
